UNITED STATES PATENT OFFICE.

GEORGE J. SAYER, OF CHICAGO, ILLINOIS.

SAUSAGE-STUFFER.

1,109,548.

Specification of Letters Patent.

Patented Sept. 1, 1914.

Application filed July 14, 1913. Serial No. 778,994.

To all whom it may concern:

Be it known that I, GEORGE J. SAYER, a citizen of the United States, residing at Chicago, in the county of Cook and State of Illinois, have invented a certain new and useful Improvement in Sausage-Stuffers, of which the following is a full, clear, concise, and exact description, reference being had to the accompanying drawings, forming a part of this specification.

My invention relates to sausage stuffing machinery and has for its object the provision of an improved device of this character in which a removable head is provided for the cylinder of the machine in combination with suitable devices which will prevent the piston from leaving the cylinder should the head be removed from the cylinder.

My invention further contemplates means in connection with the cylinder head whereby it is adjustable so that the outlet tubes may be set to face in any one of a given number of different directions. By this I mean that the cylinder head which has the outlet tubes can be rotated throughout the greater portion of 360° so that it can face in any desired direction, so that the machine when standing near a wall can have these outlet tubes pointing in the most convenient direction desired. The cylinder head is mounted upon a swinging bridge and when this swinging bridge is rotated out of its normal position, the cylinder head may be thus rotated to whatever position desired.

I am describing herein one specific form which my invention may take without meaning to have it understood that this is the only form of my invention, the particular form chosen being for illustrative purposes merely. This particular form is set forth in and will be described in connection with the accompanying drawings, in which—

Figure 1 is a longitudinal sectional view of the top of a cylinder and my improved cylinder head; Fig. 2 is a top view partly in section, illustrating the cylinder head and the protective means used to prevent egress of the piston; Fig. 3 is a side view of the upper portion of the cylinder and my improved cylinder head, and Fig. 4 is a top view thereof.

My improved device consists of a cylinder 1 in which a piston 2 is adapted to oscillate, the piston being adapted to force sausage

meat out through openings of tubes 3 and 4 provided upon the cylinder head 5. The cylinder head 5 has an annular groove 6 conical in cross-section as shown, so as to engage with a conical projection 7 provided upon the cylinder to effect a good joint. The cylinder head 5 is pivotally mounted upon a shaft 8, which shaft has a head 9 and a restricted neck 10 by means of which through the agency of the collar 11 the said cylinder head is rotatably mounted upon said shaft 8. The shaft 8 through the agency of the screw threads 12 is mounted in a bridge 13. The upper end of the shaft 8 is provided with a handle 14 so that it may be rotated.

It will be seen of course with the bridge 13 in the position shown, operation of the handle 14 will serve either to press the cylinder head down tightly upon the cylinder or else to elevate the same so as to remove the groove 6 from the projection 7. The bridge 13 by means of the bearing 15 is rotatably mounted upon the stud 16 secured in the ear 17 of the cylinder. The nut 18 holds the bearing 15 in place upon the stud. The opposite extremity of the bridge member 13 is bifurcated forming the two arms 19 and 20 which are adapted to coöperate with a swinging bolt 21 pivotally mounted upon the shaft 22. The shaft 22 is secured within ears 23 provided upon the cylinder 1. When the bolt 21 is in the position shown in Fig. 1, it of course prevents elevation of that particular extremity of the bridge member 13, and through the agency of the handle 14 the cylinder head may be screwed tightly into place. Now should it be desired however to open the cylinder, then the bolt 21 is swung outwardly as shown in dotted lines at 21^a in Fig. 3, whereupon the cylinder head having been previously raised to clear the projection 7, said bridge member 13 together with the cylinder head may be swung about the stud 16 for instance, into the dotted position shown at 5^a in Fig. 2. The bearing 15 is provided with an overhanging portion 24 shown more clearly in Fig. 4. This overhanging portion when the cylinder head is moved out of the way into the dotted position, moves across the top of the cylinder into the position shown at 24^a in Fig. 2 so that it projects over the interior of the cylinder, thus to prevent the piston from coming out, even though the pressure may be applied to the other side

of the piston. In this way it will be seen that as the cylinder head is swung out of the way, other means partly cover the opening to prevent escape of the piston. The 5 overhanging portion 24 is provided at 25 with a cut-away portion so that should it really be desired to permit removal of the piston, that then this bridge 13 is swung around 180° from the position occupied in 10 Fig. 4, and under that condition the cut-away portion 25 registers with the inner wall of the cylinder so that the piston may come out. The overhanging portion 24 is also provided with a pair of screws 26, 26 15 which are normally in place and which prevent rotation of the bridge 13 throughout an arc of 180° unless said screws are actually removed, which would have to be done before the machine could be put in position 20 to permit removal of the piston. The cylinder head, as before stated, has two pipes 3 and 4 which lead outwardly to conduct the sausage meat from within the cylinder. These tubes, it may be at times desirable to 25 point in different directions for instance from that shown in Fig. 4. My improved construction has means to accomplish this result. For this reason each of the projections from these outlet pipes is provided 30 with a socket 27, 27 and a further socket 28 is provided upon one of the ribs of the cylinder head. These sockets are adapted to coöperate with a plunger 29, which plunger is seated within a bearing 30 provided in 35 the bridge 13. A spring 31 normally presses the plunger downwardly and the thumb-piece 32 permits elevation of this plunger out of the socket so that the cylinder head 5 may be rotated into a desired position. 40 This plunger 29 may coöperate with one of the other sockets to again hold this cylinder head 5 against further rotation after it has been placed in its desired position. It will thus be seen that the cylinder head 5 being 45 rotatable may be moved to occupy any one of a plurality of predetermined different positions to thereby change the direction of the outlets 3 and 4 to accommodate the placing of other apparatus as may be required. 50 From what has been described it is thought that the nature of my invention will be clear, as will also the fact that changes and modifications may be readily made without departing from its spirit. 55 Having however thus described one form of my invention, what I claim as new and desire to secure by Letters Patent is:

1. In a machine of the character described the combination with a cylinder, of a cylinder head, means for carrying the cylinder head and moving the same into and out of position, and means provided upon said last aforesaid means adapted when said cylinder head is moved away from its position of closure, to project beyond the inner wall of said cylinder to prevent escape of the piston.

inner wall of said cylinder to prevent escape of the piston.

2. In a machine of the character described the combination with a cylinder, of a cylinder head, means for rotatably carrying 70 said cylinder head, and a locking device interposed between said means and said cylinder head.

3. In a machine of the character described the combination with a cylinder, of a cylinder head, means for rotatably carrying said cylinder head, and a locking device interposed between said means and said cylinder head, said locking device including a spring 75 pressed plunger and a socket.

4. In a machine of the character described the combination with a cylinder, of a cylinder head, a bridge for rotatably carrying said cylinder head, and a locking device interposed between said bridge and said cylinder head, said locking device including a spring 80 pressed plunger and a socket.

5. In a machine of the character described the combination with a cylinder, of a cylinder head, a bridge for rotatably carrying 85 said cylinder head, and a locking device interposed between said bridge and said cylinder head, said locking device including a spring pressed plunger and a plurality of 90 sockets carried by said cylinder head.

6. In a machine of the character described the combination with a cylinder, of a cylinder head, means for carrying the cylinder head and moving the same into and out of position, and a bracket provided upon said last aforesaid means adapted when said cylinder head is moved away from its position of closure, to project beyond the inner wall 100 of said cylinder to prevent escape of the piston.

7. In a machine of the character described the combination with a cylinder, of a cylinder head, means for carrying the cylinder head and moving the same into and out of position, and a bracket provided upon said last aforesaid means adapted when said cylinder head is moved away from its position of closure, to project beyond the inner wall 110 of said cylinder to prevent escape of the piston, said bracket having a cut-away portion 115 so that when said means is moved a given distance away from its normal position, said cut-away portion registers with the inner wall of said cylinder to permit escape of said piston.

8. In a machine of the character described the combination with a cylinder, of a cylinder head, means for carrying the cylinder head and moving the same into and out of position, a bracket provided upon said last aforesaid means adapted when said cylinder head is moved away from its position of closure, to project beyond the inner wall of 125 said cylinder to prevent escape of the piston, said bracket having a cut-away portion 130

so that when said means is moved a given distance away from its normal position said cut-away portion registers with the inner wall of said cylinder to permit escape of 5 said piston, and removable stops provided upon said bracket to prevent said bracket occupying the registering position aforesaid without removal of said stops.

9. In a machine of the character described 10 the combination with a cylinder, of a cylinder head, a rotatably mounted bridge for carrying the cylinder head to move the same into and out of position, and a projection provided upon said bridge adapted to overhang the inner wall of said cylinder when 15 said bridge is moved away from its normal position of cylinder closure.

10. In a machine of the character described the combination with a cylinder, of 20 a cylinder head, a rotatably mounted bridge for carrying the cylinder head to move the same into and out of position, a projection provided upon said bridge adapted to overhang the inner wall of said cylinder when 25 said bridge is moved away from its normal position of cylinder closure, and a removable holding device for the unmouted extremity of said bridge.

11. In a machine of the character de-

scribed the combination with a cylinder, of 30 a cylinder head, means for carrying the cylinder head and moving the same into and out of position, means provided upon said last aforesaid means adapted when said cylinder head is moved away from its position 35 of closure, to project beyond the inner wall of said cylinder to prevent escape of the piston, and means provided upon said first aforesaid means to force said cylinder head in place upon the cylinder.

12. In a machine of the character described the combination with a cylinder, of 40 a cylinder head, means for carrying the cylinder head and moving the same into and out of position, and means provided upon 45 said last aforesaid means adapted when said cylinder head is moved away from its position of closure, to project beyond the inner wall of said cylinder to prevent escape of the piston, said last aforesaid means including a screw threaded shaft.

In witness whereof, I hereunto subscribe my name this fifth day of June, A. D. 1913.

GEO. J. SAYER.
